X-RAY SYSTEM

Filed Dec. 1, 1931

UNITED STATES PATENT OFFICE

HARRY F. WAITE, OF NEW YORK, N. Y.

X-RAY SYSTEM

Application filed December 1, 1931. Serial No. 578,256.

The object of my invention is to provide a system in which a sudden disruption of the X-ray tube will not do damage to other parts of the system; and a further object is to provide a system wherein there will be a proper electron flow through the X-ray tube regardless of the volume of current passing through the tube. These and other objects are accomplished by my invention, one embodiment of which is hereinafter more particularly set forth.

For a more particular description of my invention, reference is to be had to the accompanying drawing, forming a part hereof, in which

The figure shows a diagrammatic view of my invention.

The source of power is an alternating current which, for convenience, is indicated diagrammatically at 1, as an alternating generator of a single phase type, although my invention is equally applicable to any source of alternating current or pulsating current suitable for X-ray work. From this generator run the usual leads 2 and 3 which are connected as will now be described.

The principal circuit is through a regulator 4, wire 5, primary 6 of a high tension transformer 7, wire 8, primary 9 of a regulating transformer 10 and thence to the wire 2.

Another circuit is from the wire 2 through the wire 11 to a regulator 12, thence through a wire 13 to the primary 14 of a step-down filament transformer 15, this transformer being for a hot cathode X-ray tube, as will appear below. From the primary 14 another wire 16 runs to the wire 3.

A third circuit is by the wire 17 connected to the wire 3, to the secondary 18 of the regulating transformer 10, and thence through a wire 19 to the primary 20 of a filament transformer 21 for a hot cathode valve tube, which will be described below, and thence through a wire 22 to the wire 2.

The induced circuits will now be considered. Beginning with the secondary 23 of the high voltage transformer 7 one wire 24 runs from this secondary to one of the cathode wires 25 of the hot cathode X-ray tube 26.

This tube 26 has a second cathode wire 27 and these wires 25 and 27 run to the secondary 28 of the filament transformer 15 and furnish the cathode heating current in the conventional manner. The tube 26 has an anode which is connected to a wire 29, which runs to the cathode of a hot cathode valve tube 30 in the conventional manner, and this tube 30 has two cathode wires 31 and 34. The wire 31 runs from the wire 29 to the secondary 35 of the transformer 21 and the wire 34 runs from this secondary to the hot cathode of the valve tube 30. The anode is connected by the wire 32 to the secondary 23 of the transformer 7.

From the foregoing, it is apparent that the regulating transformer has its primary in circuit with the primary of the high voltage transformer, and its secondary in circuit with the primary of the filament transformer for the hot cathode valve tube. The regulating transformer is carefully wound so as not to interfere with the normal operation of the hot cathode X-ray tube, but if a heavy current be passed through this X-ray tube for the purposes of making an X-ray plate or for other purposes, greater power is drawn from the transformer 7 and greater power is delivered at the primary 6 of this transformer and the corresponding increase of power is delivered to the primary 9 of the regulating transformer 10 with the result that increased power is given to the filament transformer 21, which in turn gives a brighter glow at the cathode of the valve tube 30 with the result that there is an increased electron discharge at the X-ray tube 26 during the fraction of a second or other time that the tube is functioning. As soon as the X-ray tube has functioned in the desired manner, only a normal current is passed through the hot cathode of the valve tube, which automatically adjusts itself in the manner above described, both for increase and decrease according to the abnormal demands on the tube 26. As these abnormal demands are generally of very short duration, as a small fraction of a second, for the taking of an X-ray plate, it is obvious that the life of the valve tube 30 is 100

greatly prolonged because its cathode is not overheated more than is absolutely essential for the functioning of the apparatus. If hand regulation were resorted to, for the purpose of governing the glow of this cathode in the tube 30, it would glow very much longer than is essential under the conditions of the system of this invention, and so the life of the tube would be correspondingly shortened.

- 10 At times the X-ray tubes 26 will short circuit and cease to function. When this occurs a corresponding increase of current tends to surge through the secondary 23 and there is a corresponding increase of power in the primary 6. At such a time there is a corresponding increase of power in the primary 9 of the transformer 10 and an instant increase in the filament current of the hot cathode valve tube so that the electron emission is 20 sufficient to carry the increased high tension current without increase of voltage across valve tube, thus preventing the target in the valve tube from becoming heated and thus giving off a gas which interferes with the proper function of valve tubes.

15 While I have shown and described one embodiment of my invention, it is obvious that it is not restricted thereto, but that it is broad enough to cover all structures that come 25 within the scope of the annexed claim.

Having thus described my invention, what I claim is:

30 In a system of the class described, a hot cathode X-ray tube, a hot cathode valve tube, 35 a high voltage transformer, and connections to both tubes, means for furnishing the hot cathode X-ray tube with a suitable heating current, a transformer and means for connecting the same to the hot cathode of the 40 valve tube, means for connecting the hot cathode valve tube with the hot cathode X-ray tube, and a regulating transformer having its primary in series with the primary of the high voltage transformer, and its secondary in series with the primary of the filament transformer of the hot cathode valve 45 tube.

In testimony whereof, I have hereunto set my hand this 24 day of November, 1931.

50 HARRY F. WAITE.
